COMBINATION COT AND RECLINING CHAIR

Chester W. Cuthell, New York, N. Y., assignor,
by mesne assignments, to Curtiss Aerocar
Company, Inc., Opa Locka, Fla., a corporation
of Florida

Application January 10, 1929. Serial No. 331,555

1 Claim. (Cl. 155—45)

My invention relates to chairs and more particularly to a combination cot and reclining chair in which a multiplicity of positions of adjustment of the chair or cot parts may be easily and 5 quickly effected.

In its preferred embodiment, the invention comprises a supporting frame, three relatively adjustable hingedly connected cot or chair parts, and a system of bracing or underslung truss 10 members arranged to adequately and strongly brace said cot or chair parts in all positions of adjustment.

The advantages of the invention, essentially structural, will be hereinafter set forth.

15 In the drawings:

Fig. 1 is a plan view of the chair, adjusted to cot position, portions of the covering therefor being broken away;

Fig. 2 is a side elevation of the structure illustrated in Fig. 1;

Fig. 3 is a rear end elevation;

Figs. 4 and 5 are views similar to Fig. 2 showing different positions of chair adjustment, and

Fig. 6 is a detail view showing the manner of 25 fastening the chair or cot covering to the frame.

The combination cot and reclining chair (see Figs. 1 and 2) comprises a supporting frame preferably constructed of metal tubing. Said supporting frame includes two side frames 10—10, 30 which at the foot of each leg thereof, may or may not be fastened, as by screws or the like, to the floor. Each said frame 10 comprises a forward leg 11, a rear leg 12, and a diagonal brace 13 extending from the foot of one said leg to the top 35 of the other. The forward legs 11, unlike the rear legs 12, and the diagonals 13, are adjustable. Each said leg, at its lower end, is pivoted as at 14 to an enlargement 15 formed at the lower end of each said diagonal. Both pairs of legs are appropriately cross-braced, the forward legs as indicated at 16, and the rear legs as indicated at 17 and 18—18.

That part of the cot or chair intended to directly support the occupant or occupants comprises a forward part, an intermediate part, and a rear part. In the absence of a better designation said forward part will be hereinafter referred to as a leg-rest 19, said intermediate part as a seat 20, and said rear part as a head or back-rest 21. Said leg-rest 19 is substantially U-shaped as is also the head or back-rest 21. Intermediately of its ends, but nearer to its open or forward end than to its rear or closed end, said head or back-rest 21 is pivotally supported as at 55 22 between and at the upper ends of the rear legs

12 of the side frames 10—10. Thus supported, said head or back-rest 21, in certain positions of adjustment, very appreciably overhangs or extends rearwardly beyond the corresponding end of its supporting frame. 60

The leg-rest 19, tho it overhangs or is extended forwardly beyond the corresponding end of said supporting frame, is pivoted nevertheless, not intermediately of its ends, but at its extreme rear end to and between the forward legs 11 of the 65 side frames 10—10. This point of pivotal support, designated as 23, unlike the pivotal support for the head or back-rest 21, serves also as a hinge connection between the leg-rest 19 and the seat 20, whereas at the forward end of the head 70 or back-rest 21, a distinctly separate hinge connection 24 between it and said seat is provided. Thus supported, the seat 20, in all chair positions of adjustment, is slightly backwardly and downwardly inclined from its forward point of support as indicated in Figs. 4 and 5. 75

The means for bracing the connected parts 19, 20, and 21, consists of an underslung longitudinally extending brace, joined as at 25—25 to the bight portion of the leg-rest 19 at one end of the 80 combination cot and chair, and joined as at 26—26 to the bight portion of the head or back-rest 21 at the opposite end of said combination cot and chair. Said brace, in its preferred embodiment, comprises an intermediate or connecting member 27, two cross-frame members 28 and 29, and end or diverging brace members 30—30 and 31—31, respectively. The diverging members 30—30 are integral with the cross-frame member 28 which extends from one to the other 90 of the side frame pieces comprising the leg-rest 19, whereas the diverging members 31—31 are integral with the cross-frame member 29 which extends from one to the other of the side frame pieces comprising the head or back-rest 21. The 95 intermediate or connecting member 27 joins the cross-frame members 28 and 29 and is pivotally fastened thereto as at 32 and 33, respectively. By bowing said cross-frame members 28 and 29 downwardly as shown, and by pivotally fastening said member 27 to said cross-frame members, a rigid underslung longitudinally extending toggle-like brace, in the cot position of adjustment, is established, which brace, due to said pivotal connections 32 and 33 may be disrupted and/or 100 reestablished, at will, for any position of adjustment. Thus organized, the brace gives adequate strength, is extremely simple, and regardless of the position of chair or cot adjustment, is at all times out of contact with and well below the cov- 110

ering 34 carried by the connected frame parts. Said covering 34 is preferably fastened to the framed parts as indicated in Fig. 6.

As a means for locking the chair parts in adjusted position, two levers 35—35 are provided. These levers 35—35 are positioned, one each at opposite sides of the chair and are pivotally fastened to the chair frame at the hinge joints 24. Each said lever, intermediately of its ends, and 10 along its underneath edge, is notched as at 36 to engage with the cross-brace or brace rod, 17 extending from one to the other of the rear legs 12—12 of the chair. By lifting said levers out of engagement with said rod and exerting either 15 a push or a pull thereon, any position of chair or cot adjustment may be effected. If desired, the chair parts may be provided with upholstery for added comfort.

A combination cot and reclining chair of the 20 character above set forth is advantageous in that, adjusted to provide a cot, no part or portion of the supporting frame is extended above the horizontal plane of the chair or cot covering. It is further advantageous in that the longitudinally extending brace is carried to the extreme ends of the chair frame, and in all positions of chair or cot adjustment gives maximum support to the overhangs. As furniture for 25 porches, steamer decks, vehicle equipment, etc., it is especially desirable in view of the simplicity 30

of construction, lightness, comfort, and cheapness of manufacture.

While I have described my invention in detail in its present preferred embodiment, it will be obvious to those skilled in the art after understanding my invention, that various changes and modifications may be made therein without departing from the spirit or scope thereof. I aim in the appended claim to cover all such modifications and changes.

What I claim is:

A chair which comprises a supporting frame including rigid rear legs, forwardly and downwardly extending braces rigidly secured thereto, and front legs pivoted at their lower ends to the forward ends of said braces, a back rest pivotally supported intermediate its ends between the upper ends of said rear legs, a seat hinged at its rear end to the forward end of the back rest, a leg rest hinged at its rear end to the forward end of the seat, downwardly bent transverse braces secured respectively to the back rest and leg rest, a link connecting said braces whereby movement of the back rest from a horizontal toward a vertical position tilts said seat and front legs rearwardly and said leg rest downwardly, and means to releasably lock the back rest in a plurality of positions.
